UNITED STATES PATENT OFFICE.

THOMAS S. HOMANS, OF BROOKLYN, NEW YORK, ASSIGNOR TO INTERTYPE CORPORATION, OF BROOKLYN, NEW YORK, A CORPORATION OF NEW YORK.

ASSEMBLER-SLIDE ADJUSTMENT FOR LINE-CASTING MACHINES.

Application filed June 10, 1925. Serial No. 36,232.

The present invention relates to improvements in line-casting machines, and especially to those of the linotype class wherein character-bearing matrices and spacers are delivered, under control of a keyboard, and assembled in a so-called assembling elevator, preparatory to the transfer of such line to the casting mechanism where a slug or type bar is cast therefrom; and the invention pertains more particularly to the assembler slide which has an upstanding finger which serves to hold the matrices together or in compact form while the line is in process of assembly, the slide being caused to advance as the matrix assembling process progresses and being provided with means for limiting its advancing motion according to the length or measure of the line to be composed, thereby preventing overfilling of the line and being also provided with means for causing operation of a signal or indicator, usually a bell, to inform the compositor when the line is nearly filled.

The primary object of the invention is to provide novel and improved means whereby a single adjustment which can be made quickly and with facility by the compositor while occupying his usual position at the keyboard of the machine, serves to set the assembler slide for a line of any desired length or measure, to set the stopping or limiting means for the slide so that the advance thereof will be arrested when the line of matrices in process of assembly has reached the measure for which it is set, and to set the indicator or bell-operating means so that the indicator will operate at the correct point in advance of the completion of the line.

To these and other ends, the invention consists in certain improvements and combinations and arrangements of parts, all as will be hereinafter more fully described, the features of novelty being pointed out particularly in the claims at the end of the specification.

In the accompanying drawing:—

Figure 1 is a front elevation of a portion of the assembling mechanism of a line-casting machine constructed in accordance with the preferred embodiment of this invention;

Figure 2 is a front elevation of the assembler slide and related devices, the slide having returned to its initial or starting po-

sition following removal of a line of matrices therefrom by ascent of the assembling elevator;

Figure 3 is a perspective view of the adjusting means for the assembler slide;

Figure 4 represents a vertical section through the adjusting means on the line 4—4 of Figure 5, portions of the assembler slide and of the cooperative auxiliary slide being shown in front elevation;

Figure 5 represents a vertical section taken axially through the adjusting means and transversely through the assembler and auxiliary slides;

Figure 6 is a detail view in top plan of a portion of the auxiliary slide;

Figure 7 is a front elevation of part of the mechanism shown in Figure 1, illustrating the means employed for operating the bell or signal for indicating where the line in course of composition is nearly filled;

Figure 8 is a detail perspective view of the pawl and cooperative means for actuating the bell hammer; and

Figure 9 represents a cross-section on the line 9—9 of Figure 7 looking toward the left.

Similar parts are designated by the same reference characters in the several views.

The present invention is applicable generally to the assembling mechanism of line-casting machines wherein an assembler slide is employed which has a finger behind which the matrices and spacers are assembled to form a line preparatory to the casting of a type bar therefrom, the assembler slide being advanced as the assembling of the line progresses, under the force exerted on the finger of the slide by the matrices as they are successively introduced into the line behind it. The preferred embodiment of the invention is shown in the accompanying drawings and will be hereinafter described in detail as applied to a line-casting machine of the well-known linotype class, but it is to be understood that the invention is not restricted to the precise construction shown as equivalent constructions are contemplated, and such will be included within the scope of the claims.

In the present instance, 1 represents the assembling elevator which in machines of the linotype class is guided to move vertically so that when the assembling of a matrix line therein has been completed, it may ascend

- and thereby transfer the matrix line from the assembler slide to a transfer carriage which operates at a relatively higher level in the machine and serves to remove the matrix line from the assembling elevator and to forward the line toward the casting point. The matrices and spacers during their assembly in the assembling elevator are supported and guided therein by the rails 2, as 5 will be understood by those skilled in the art. The matrices are delivered from the magazine or magazines in which they are stored through manipulation of the usual keyboard, to an assembling belt 3, and this 10 belt delivers the matrices to the continuously revolving star-wheel 4 which stacks the matrices successively in the line and advances the line in process of assembly, toward the left in Fig. 1.
- 15 20 The assembler slide 5 which is movable in a direction parallel to the length of the matrix line, has a finger 6 which extends upwardly therefrom into the channel formed between the rails 2 of the assembling elevator, so that this finger will occupy a position 25 in front of the matrix line as the latter is assembled. The assembler slide is preferably supported on anti-friction rollers 7 and 8 in order to minimize frictional resistance to its 30 movement, and the slide is mounted on a bracket 9 which is fixed to the relatively stationary main frame of the machine.
- 35 The present invention provides means whereby a single adjustment that can be easily and quickly made by the compositor, will serve to determine the limit of movement of the assembler slide to conform with any desired length or measure of the matrix lines to be composed and to correspondingly 40 set the means which operates the bell or other indicator to inform the compositor when the matrix line of the selected measure has been nearly filled. Preferably, and as 45 shown in the present instance, such means comprises a revoluble member 10 having a pinion 11 fixed thereto and arranged to co-operate with a toothed rack 12 on the assembler slide so that advancing movements of the assembler slide during the assembling 50 of a line will cause corresponding rotary motion of the member 10, and rotation of the member 10 in an opposite direction will cause return of the assembler slide to its initial or starting position. The member 10 is 55 preferably formed with a hub 13 which is fitted to rotate on a pin or journal 14, the rear end of which may be fixed to a part 9^a of the bracket 9 by a nut 15 or other suitable means. The pin 14 has a thrust 60 collar 16 thereon which is arranged to engage and to sustain a forward thrust when such is exerted on the member 10. The pinion 11 is preferably fitted in an annular recess 17 formed in the rear side of the member 10, and a guard flange 18 is preferably applied 65

to the rear side of the pinion, the rack portion 12 of the assembler slide preferably operating between this flange 18 and the body portion of the member 10 and thus insuring maintenance of the working relation between the rack and the pinion 11. The pinion 11 and guard 18 may be secured to the member 10 by a suitable number of screws 19 which extend into a section 20 which provides a removable front 70 or cover for the member 10. The member 10 is formed interiorly with a chamber 21 in which is accommodated a spring 22, this spring serving to rotate the member 10 in a direction to effect the return of the assembler slide to its initial position after an assembled line of matrices has been removed from the assembler slide. Preferably, the spring is of coiled or spiral form, its inner 75 end being fixed at 23 to the relatively fixed non-rotatable pin 14 while its outer end is attached, by a pin 24, or other suitable means, to the rotatable member 10.

80 The member 10 of the adjusting means is provided with a setting member which determines the range of movement of the assembler slide in accordance with the line measure for which it is set and also determines the point during the assembling of the line at which the indicator bell will operate. Preferably, and as shown, this setting member 85 comprises a knob 25 which is capable of rotation relatively to the member 10 for the purpose of setting it for different line measures and means is provided by which the knob is connected to rotate in unison with the member 10 during the operation of the assembler slide. As shown, the knob is fitted at its inner end 26 to rotate on a stem or sleeve 27 which projects forwardly from and forms a part of the forward section 20 of the member 10, this stem or sleeve being fitted rotatably on the forward portion of the pin 14. A toothed clutch or equivalent 90 device which is graduated so that the knob may occupy various positions of rotation relatively to the member 10 corresponding with the graduations of line measurement, is provided between the knob and the member 10. As shown, the forward side of the front 95 section 20 is formed with an annular toothed clutch face 28 and the rear face of the knob is formed with a corresponding annular toothed clutch face 29, the number and spacing of the clutch teeth being such that the knob may be set in a number of angular 100 positions relatively to the member 10 which correspond with the graduations of the line measurements. To facilitate the setting of the knob for different desired line measures, a pointer 30 is fixed to one of the parts, preferably the member 10, and the other part, preferably the knob, is provided with a dial 31 having suitable graduations 32 thereon 105 which correspond with the different settings 110

115

120

125

130

of the knob for the various line measures, the indicating scale on the dial cooperating with the pointer 30 on the member 10. Means is provided for normally holding the 5 knob in engaged relation with the member 10 so that the knob will rotate in unison therewith, and which permits disengagement of the knob from the member 10 to enable changing of the line measure setting. As 10 shown, the hub of the knob is formed with a chamber 33 to accommodate a compression spring 34 which is preferably coiled about the stem or sleeve 27, the forward end of the spring bearing against a ring or flange 15 35 which may be threaded or otherwise fixed to the stem 27 and the rear end of the spring bearing against the shoulder provided by the bearing portion 27 of the knob. The action 20 of this spring is to yieldingly force the knob rearwardly to cause its clutch teeth to engage those of the member 10 and to maintain the clutch teeth in engagement, although permitting the knob to be drawn forwardly when sufficient pull is exerted thereon by the hand of the compositor, whereby 25 the clutch teeth of the knob will be disengaged from those of the member 10 and the knob while held in its forward position may be freely rotated in either direction relatively to the member 10 to reset the device 30 for either a longer or a shorter line measure, as may be desired. When the knob is released after resetting, the spring 34 will act automatically to re-engage the knob with 35 the member 10. The outer end of the pin 14 may be provided with a disk 36 to fit in the chambered hub of the knob and thus provide a steady support for the knob while the latter is drawn forwardly for resetting 40 purposes.

The setting of the knob with respect to the member 10 determines the limit of movement of the assembler slide during the assembling of a line. The knob has a pin or stop 37 45 fixed thereon, and the position of this pin around the shaft 14 which constitutes the axis of rotation of the knob, will vary with the different line settings of the knob; and as the knob rotates in accordance with the 50 advancing movement of the assembler slide during the process of assembling a line, this pin 37 will operate, through the medium of stop means, to limit the advance of the assembler slide to conform with the line measure 55 for which the knob is set. The stop means, as shown, comprises a slide 38 which is auxiliary to the assembler slide, it being inactive or immovable during a portion of the advancing movement of the assembler slide, but movable concurrently or in unison 60 with the assembler slide, under the influence of the pin 37, during the final portion of the advancing movement of the assembler slide, and the auxiliary slide is arranged to abut 65 against a stop when the assembler slide has

advanced to the proper limit, as determined by the line measure for which the knob is set, the consequent arresting of the motion of the auxiliary slide preventing further motion of the pin 37 whereby further advance of the assembler slide is arrested. The auxiliary slide is preferably mounted to slide freely in guides 39 and 40 which are supported by the bracket 9, so that the auxiliary slide is located alongside the assembler 75 slide 5 and is movable in substantial parallelism therewith, although the auxiliary slide is capable of reciprocating independently of the assembler slide. One end of the auxiliary slide is located in the path of 80 the pin 37 on the knob when the pin reaches its lower position or a position below the center of rotation of the knob, and the opposite end of the auxiliary slide is formed with a head 41 which is adapted to abut against 85 the end of the guide 39 and thus limit the movement of the auxiliary slide toward the right in Figure 1, the head carrying a projection 42 which is arranged to abut against a shoulder or stop 43 which is in fixed relation to the bracket 9 whereby the movement 90 of the auxiliary slide in accordance with the advancing movement of the assembler slide will be arrested when the assembler slide reaches its limit as determined by the line 95 measure setting of the knob. A tension spring 44 is attached at one end to the auxiliary slide and at its other end to a relatively stationary part of the machine, as, for example, the guide 40, this spring acting to 100 return the head 41 on the slide against the guide 39 during the receding movement of the pin 37 incident to the return of the assembler slide to initial position but permitting the auxiliary slide to be advanced by 105 the pin 37 when the latter advances during the assembling of a line.

The spring 22 acts constantly to return the assembler slide to its normal or initial position, and in order to avoid pressure of the assembler slide finger 6 against the line of matrices during the intervals between the introduction of the matrices therein, and thus prevent undesirable pressure of the last introduced matrix in the line against the star-wheel 4, a brake 45 is provided, this brake allowing the assembler slide to be advanced without obstruction, to an extent sufficient to admit each successive matrix into the line, but acting after each successive advance of the assembler slide has been completed, to prevent retrograde motion of the assembler slide which, if permitted to occur, would force the line of matrices in process of assembling, backwardly against the star-wheel. The brake may consist, as shown, of a lever which is pivoted to rock freely on a screw or other pivotal support 46 and this lever carries friction shoes 47 between which the assembler slide extends. When the brake 115 120 125 130

lever occupies the position about its pivot as shown in Figure 2, the friction shoes thereon will permit the assembler slide to move without obstruction, and this occurs 5 during the restoring of the assembler slide to its normal or initial position; at other times, however, a spring 48 acts on the brake to rotate it about its pivot 46, so that the friction shoes thereon bear on the upper and 10 lower edges of the assembler slide so as to prevent retrograde motion of the assembler slide, or motion toward the right in Figure 1, although permitting advancing movements of the assembler slide, incident to the 15 assembling of the matrices in the line, without substantial resistance by the brake. The upper brake shoe 47 is narrowed and arranged to cooperate with the smooth upper edge 5^a of the slide at the rear of the rack 20 teeth 12 thereon, thus avoiding interference with its action by the rack teeth.

Means is provided for automatically retracting the brake 45 to release and permit return of the assembler slide to its normal 25 or initial position incident to the ascent of the assembling elevator which transfers the complete assembled matrix line to the transfer carriage. Such means is shown in the present instance, it comprising a lever 49 which is pivoted at 50 to the bracket 9, the lever at one side of its pivot carrying a pin 30 or projection 51 which is arranged to ride upon a cam 52 on the lower or free end of the brake lever. The opposite end 53 of this lever is in a position to be acted on and 35 pressed downwardly by the portion 54 on the assembling elevator while the latter is in its lower or line-receiving position. While the assembling elevator is in this position, the 40 end of the lever 49 which carries the pin 51 will be held in elevated position and the pin 51 will be beyond or clear of the cam 52, so that the spring 48 may act to hold the 45 brake in operative relation with the assembler slide and to prevent retrograde motion of the latter after each advance thereof incident to the introduction of a matrix into the line. The parts are shown in this position in Figure 1. When the assembling elevator ascends to remove an assembled matrix 50 line from the assembler slide, the end 53 of the lever 49 is engaged by the abutment 55 on the elevator and thus caused to rise and the opposite end of the lever which carries the pin 51 will descend, causing the pin 51 to ride upon the cam 52, and in so doing, to swing the brake lever from the position 55 shown in Figure 1, into the position shown in Figure 2, the friction shoes 47 being then 60 disengaged from the assembler slide, thus releasing the latter, so that it may return freely to its normal or initial position, the assembler slide being shown in this position in Fig. 2. The assembler slide is arrested 65 upon reaching its normal or initial posi-

tion by a stop 56 on the slide which is arranged to abut against the relatively fixed guide 57.

The mode of operation of assembling mechanism constructed as hereinbefore described, is substantially as follows: The matrices designated M are delivered to the assembling elevator from the magazine or magazines, through the operation of the usual keyboard, by the assembler belt 3, and the usual star-wheel 4, and the star-wheel introduces the matrices into the channel of the assembling elevator which is provided between the rails 2 thereof and behind the finger 6 of the assembler slide. As the matrices are successively introduced into the line by the star-wheel, the finger 6, together with the assembler slide, are pushed toward the left in Fig. 1 to accommodate the incoming matrices, this advancing movement of the assembler slide being opposed by the spring 22 which constantly acts to return the assembler slide to its initial position, and the assembler slide is held against retrograde motion, after each advance thereof, by the brake 45 which permits each advance of the slide to take place but clutches the slide and thus prevents retrograde motion thereof. During the assembling of the line, the brake-tripping lever 49 will be held in its inoperative position, as shown in Figure 1, as the assembling elevator at this time will be in its lower position and it will hold the left-hand end of the lever 49 in its depressed position.

During the assembling of a line, the line-setting device which comprises the member 10 and the knob 25 will rotate in a clockwise direction, as viewed in Figure 1, owing to the connection maintained between the setting device and the assembler slide by the pinion 11 and the cooperating rack 12, and as the knob 25 is held in clutched relation with the member 10 at this time by the spring 34, the pin 37, which rotates with the knob, will advance through an arc, the length of which is determined by the setting of the knob relatively to the member 10, until it reaches a position to engage the right-hand end of the auxiliary slide 38. During the first part of the advancing movement of the assembler slide incident to the assembling of the line, the auxiliary slide 38 will remain stationary while the assembler slide advances, but as soon as the pin 37 engages the end of the auxiliary slide 38, the auxiliary slide will be picked up and caused to advance concurrently or in unison with the further or continued advance of the assembler slide, and as the projection 42 approaches the stop 43 its distance therefrom will afford a visual indication of the length of the unfilled part of the line. The concurrent advance of the assembler slide and the auxiliary slide will continue until 125 130

the projection 42 on the auxiliary slide abuts against the fixed stop 43, whereupon further advance of the auxiliary slide will be prevented, and, in consequence, the movement 5 of the pin 37 and the knob 25 and member 10 which rotate therewith will be arrested. As the knob 25 and member 10 at this time are in clutched relation and the member 10 is connected to the assembler slide through 10 the pinion 11 and rack 12, the arresting of the motion of the pin 37 by the auxiliary slide 38 will arrest the further advance of the assembler slide and its finger 6. Overfilling of the line is thereby prevented.

15 When the line has been completed, the assembling elevator may be caused to ascend, in the usual way, to transfer the matrix line to the transfer carriage. The ascent of the assembling elevator causes the 20 lever 49 to act so that the pin 51 thereon will ride on the cam 52 and thus shift the brake 45 to release the assembler slide, whereby the latter is permitted to return to its initial position under the influence of the 25 spring 22, as shown in Fig. 2, and the anti-clockwise rotation of the setting device incident to the return motion of the assembler slide retracts the pin 37, thus permitting the auxiliary slide 38 to return to its normal 30 or initial position, as determined by the abutment of the head 41 on this slide against the guide 39, under the tension of the spring 44. When the assembling elevator again descends to its lower line-receiving position, 35 the lever 49 is again operated to release the pin 51 thereon from the cam 52, thus permitting the brake to act on the assembler slide under the influence of its spring 48.

The limit of advancing movement of the 40 finger 6 of the assembler slide determines the length or measure of the matrix line which the assembling elevator may receive, and this limit of movement is determined by the length of the arc through which the pin 45 37 may swing until arrested by the engagement of the projection 42 on the auxiliary slide 38 with the fixed stop 43. The length of the arc through which the pin 37 may travel, commencing with the beginning of 50 the composition of the matrix line and ending with the arresting of the motion of the auxiliary slide 38 by the engagement of its projection 42 with the fixed stop 43, is determined by the position in which the knob 55 25 is set relatively to the member 10. For example, in Figure 3, the knob is set relatively to the member 10 so that the pointer 30 on the latter member registers with the numeral 14 on the scale of the dial on the 60 knob. With such setting of the knob, the pin 37 will be enabled to swing through an arc of a length which will enable the finger 6 on the assembler slide to advance during the composition of the matrix line until a 65 line having a length or measure of fourteen

ems has been composed. When it is desired to compose lines of greater or less length, it is only necessary for the compositor to grasp the knob 27 and to draw the same forward in opposition to the spring 34, thus disengaging the clutch teeth 28 and 29, and to rotate the knob relatively to the member 10, while the knob is held in its forward position, until the numeral on the scale 32 corresponding with the length or measure of the line to be composed, is opposite to the pointer 30, whereupon the knob may be released and the clutch teeth 28 and 29 will be caused to re-engage by the action of the spring 34. Such adjustments of the knob 80 set the pin 37 at different distances away from the end of the auxiliary slide 38 as the starting points in the travel of the pin 37 and thus vary accordingly the distance through which the finger 6 on the assembler 85 slide may travel before it is arrested.

The setting of the knob to determine the line measure may also serve to set the device which operates the bell or other means usually employed to indicate to the compositor when the line of any given measure has been nearly filled. For example, a bell-ringing device 58 may be carried on or otherwise actuated by the auxiliary slide 38, this device being operative to sound the bell 59 95 when the filling of the line has approached within a predetermined point of completion.

The bell ringing device 58 as shown comprises a hammer or clapper which is pivoted at a point intermediately of its length to the bracket 9, as by a shouldered screw 60, the hammer having on its left-hand end an overhanging forwardly-extending inclined flange 61. A gravity pawl 62 is pivoted to the head 41 of the auxiliary slide, this pawl having an inclined rearwardly-extending flange 63 at its lower end which is positioned to engage the flange 61 on the bell hammer as the auxiliary slide moves toward the left, thereby first lifting and then releasing this end of the hammer so that the tensioned spring 64 will cause the opposite end of the hammer to strike and sound the bell. The pivoting movements of the pawl 62 are limited in 100 both directions by suitable stop pins 65 and 66, the pin 66 acting to sustain the pawl in position to raise the flange 61 on the hammer during the left hand stroke of the auxiliary slide, but the stop pins will allow the pawl 105 to have a latching or idling movement during the right hand movement of the auxiliary slide which returns it to normal position.

110 By operating the alarm bell or other indicator in this way, the bell or indicator will always inform the compositor when the line has progressed to within a predetermined degree of completion, irrespective of the 115 length or measure of the line for which the 120 125 130

assembling mechanism is set, as the auxiliary slide 38 will be picked up and advanced by the pin 37 always at a given point in advance of the limit of movement of the 5 finger 6, and this relationship will not be altered or disturbed by setting of the knob for different line measures.

I claim:—

1. In a line-casting machine having an assembler slide for determining the lengths of composed matrix lines, a dial member capable of being set in different relationships with the slide for different line measures, and carrying a stop member and stop means cooperative with said stop member on the dial member for limiting the movement of the slide to the line measure as determined by the setting of the dial member.

2. In a line-casting machine having an assembler slide capable of advancing to different extents in accordance with different line measures, a rotatable dial member movable in accordance with the movements of said slide and capable of being set in different relationships therewith to conform with different line measures, a stop member in fixed position on the dial member and stop means cooperative with the stop member to limit the advance of the slide in accordance with a given setting of the dial member.

3. In a line-casting machine having an assembler slide capable of advancing to different extents in accordance with different line measures, a rotatable member connected to operate in unison with the movements of the slide, a dial member having disengageable toothed clutch means for connecting it to said member in different relationships in conformity with different line measures and 40 to rotate in unison with said member, said dial member having a stop member thereon and stop means arranged to cooperate with the stop member on the dial member to limit the advance of the slide in accordance with a given setting thereof.

4. In a line-casting machine having an assembler slide for determining the measure of composed matrix lines, adjustable means for setting the slide for different line measures comprising a rotatable member connected to operate in unison with the movements of said slide, means acting on said member in a direction tending to retract the slide, a dial member having jaw-clutch means 55 for connecting it, in different set relationships with said rotatable member in conformity with different line measures, to rotate with said rotatable member, and stop means including a stop member on the dial member set by the setting of the dial member and operative to limit the movement of the slide in accordance with the line measure setting of the dial member.

5. In a line-casting machine having an assembler slide capable of advancing to differ-

ent extents in accordance with different line measures, a rotary member connected to the slide to operate in unison therewith and having a spring acting thereon to return the slide to its normal initial position, a dial member, annular toothed means being provided between the rotary and dial members to connect said members to rotate in unison in different relationships conforming with different line measures, and stop means governed by the setting of the dial member for arresting the advance of the slide in accordance with the line setting of the dial member.

6. In a line-casting machine having an assembler slide capable of advancing to different extents in accordance with different line measures, a rotary member connected to the slide to operate in unison with the advancing and return movements thereof, a setting member, toothed means graduated in accordance with different line measurements being provided between said members for causing them to rotate in unison, said members being relatively movable axially to engage and disengage said toothed means, the dial member being rotatable relatively to said rotary member while the toothed means is disengaged, to enable setting of the dial member for different line measures, and stop means for the slide controlled by the setting member.

7. In a line-casting machine having an assembler slide for determining the measure of composed lines of matrices, a rotary member connected to the slide to operate in unison therewith, a setting member capable of rotation and also axial motion relatively to said rotary member, opposite annular toothed means connecting said members to rotate in unison, the relative axial motion between the members enabling the toothed means to be disengaged and the setting member to be adjusted relatively to the rotary member into different positions corresponding with different line measures, means acting to maintain engagement of said toothed means, and means governed by the adjustment of the setting member for controlling the range of movement of the slide.

8. In a line-casting machine having an assembler slide which determines the measure of lines of matrices, a rotary member connected to operate in unison with the slide, a dial member adjustable relatively to said member, said members having annular series of teeth spaced circumferentially to connect them in different rotative relationships to conform with different line measures, and to move in unison therewith, said dial member carrying a stop, and stop means for the slide arranged to be engaged by the stop on the dial member when the slide reaches a predetermined position conforming with the setting of the dial member.

9. In a line-casting machine having an assembler slide capable of advancing to different extents in accordance with different line measures, a stop member for the slide 5 movable independently of said slide, and means capable of being set in different relationships with the slide to conform with different line measures and operative, when the slide has advanced to a predetermined 10 point conforming with the line setting for which said means is set, to actuate the stop member to preliminarily advance it and to subsequently cause it to arrest the advance of the slide.
- 15 10. In a line-casting machine having an assembler slide capable of advancing to different extents to conform with different line measures, a stop member for the slide with respect to which the slide is movable independently and also in unison, and a setting member capable of being set in different relationships with the slide and having means for moving it in unison therewith, said setting member having a stop the position of 20 which is determined by the adjustment of said setting member, said stop being arranged to engage the stop member, after the slide has advanced to a predetermined extent, and to actuate said stop member to 25 arrest the advance of the slide.
- 30 11. In a line-casting machine having an assembler slide capable of being advanced
- to different extents in accordance with different line measures, an auxiliary slide capable of movement independently of and also 35 in unison with the assembler slide, a setting member capable of being set for different line measures and embodying means for controlling the point in the advance of the assembler slide at which the auxiliary slide 40 commences to advance in unison therewith, and an indicator operative by the auxiliary slide when it reaches a predetermined point during its advance in unison with the assembler slide. 45
12. In a line-casting machine having an assembler slide capable of being advanced to different extents in accordance with different line measures, an auxiliary slide capable of movement independently of and also in unison with the assembler slide, means for causing the auxiliary slide to commence to advance in unison with the assembler slide after the latter has independently advanced to a variable extent, a signal for indicating 50 when the line being composed is nearly filled, and means including a pawl carried by the auxiliary slide for operating the signal when the auxiliary slide has reached a predetermined point in its advance. 55
- 60 In testimony whereof I have hereunto set my hand:

THOMAS S. HOMANS.
